UNITED STATES PATENT OFFICE

2,023,151

CONTAINER

Harry Sebell, Boston, Mass., assignor of one-half
to Arthur H. Parker, Lexington, Mass.

Application November 15, 1933, Serial No. 698,131

10 Claims. (Cl. 220—48)

This invention relates to hermetically sealed containers which may be used for packaging food products, paint, etc., and especially to a container which is opened for discharging the contents by tearing a tear strip loose from the wall of the can.

Hermetically sealed containers with tear strips are usually constructed so that the tear strip portion is united to the wall of the container by an 10 easily tearable connection which before it is torn loose from the container forms an hermetic seal between the tear strip and the wall of the container. One convenient way of providing such a tear strip is to form in the wall of the container a line of weakness which is shaped to define the tear strip.

One of the objects of the invention is to provide improvements in hermetically sealed containers according to which the tear strip portion 20 of the wall of the container has a closure element permanently secured thereto, and which is so constructed that after the container has been opened by tearing the tear strip loose from the wall of the container, said closure functions as a means in addition to the tear strip for closing the pouring opening.

A further object of the invention is to provide improvements in containers in which said closure for the pouring opening will have a friction fit 30 with the container so as to tightly close the opening.

A further object of the invention is to provide a container of the above type in which the tear strip, when it has been torn loose from the container to open the pouring opening, operates as a hinge for the closure element.

A further object of the invention is to provide improvements wherein the closure member also serves as a means for protecting the line of weakness before the container is opened and while it is being shipped so as to obviate the possibility of the container being accidentally punctured at said line of weakness.

Other objects of the invention are to provide further improvements relating to the opening of containers which will be more fully hereinafter set forth.

In illustrating the invention I have shown it as applied to a container in the form of a sheet metal can, but I desire to state that the invention is not limited in its application to containers of the sheet metal can type but is applicable to other types of containers. Hence, when the term 55 "can" is used in the following description and in

the claims it is intended to be used in a generic sense as including any suitable container.

In the drawing wherein I have illustrated a selected embodiment of the invention, Fig. 1 is a top view of a container in the form of a sheet metal can embodying my invention showing the closure plug removed, said view illustrating the can before the closure plug is applied to the tear strip portion of the can wall;

Fig. 2 is a top plan view of the closure plug; 10

Fig. 3 is an edge view thereof;

Fig. 4 is a section through a can on the line 4—4, Fig. 1 but showing the closure plug in position attached to the tear strip and also illustrating how the tear strip may be torn loose from the 15 wall of the can when it is desired to open the pour opening;

Fig. 5 is a sectional view similar to Fig. 4 but showing the tear strip torn partially loose from the can and the pouring opening open; 20

Fig. 6 is an enlarged sectional view on the line 6—6, Fig. 1;

Fig. 7 is a section on the line 6—6, Fig. 1 but showing the closure plug in place.

In the drawing 1 indicates a can made of sheet 25 metal and having the side walls 2 and the end 3. This end may be secured to the side walls of the can in any appropriate or usual way and merely as illustrating one familiar way of making a can I have shown the top or end 3 as having the periphery 4 that encircles the end of the can body and is crimped and soldered thereto thereby forming an hermetic seal.

In making my improved can one of the walls thereof, and preferably an end wall, such as the 35 end wall 3, will be provided with a tear strip portion which is united to the wall by a readily tearable connection so that when pulling strain is applied to the tear strip it will be torn from the wall along the line of said readily tearable connection. The tear strip when thus torn partially loose from the wall will provide a pouring opening. This readily tearable connection between the tear strip and the wall can conveniently be provided for by forming the wall of the can with 45 a line of weakness and one way of providing the line of weakness is by forming a suitable score line in the can end. As illustrated in Fig. 1 the can end is formed with the line of weakness indicated at 5 which is shown as having a substantially U shape, although the particular shape of this line of weakness may be varied without departing from the invention.

As stated above this line of weakness can be formed by scoring the can or partially cutting 55

through the wall of the can along the line of weakness as shown in Fig. 6. The portion partially enclosed by the line of weakness constitutes a tear strip which may be torn from the wall of the can along the line of weakness thereby to provide a pouring opening 7.

The shape of the pouring opening will, of course, depend upon the shape of the line of weakness 5. This line of weakness is formed so as to only partially enclose the tear strip 6 so that when said tear strip has been torn from the wall of the can along the full length of the line of weakness said tear strip will still be connected integrally with the wall of the can. With the construction shown in Fig. 1 the tear strip when torn loose from the can is in the form of a tongue which is still integrally connected with the can at the point 8 and with this construction the tear strip may be used as a partial closure for the pouring opening 7.

20 One feature of my present invention relates to a novel construction wherein the tear strip 6 has a closure member permanently secured thereto which is constructed so that when the can has been opened the return of the tear strip to its original position will cause the closure member to have a friction fit with a portion of the can thus tightly closing the pouring opening.

This closure member is indicated at 11 and it is permanently secured to the end of the tear strip portion 6 in some suitable way as by spot welding it thereto as indicated at 17.

In order that the closure member 11 may function as a friction plug for closing or sealing the pouring opening I have provided the following construction. The portion of the wall of the can circumjacent the tear strip portion 6 is deformed to provide a recess 9 having vertical walls 14, the line of weakness 5 being formed in the bottom 10 of the recess. The closure plug 11 is of a size and shape to fit tightly within the recess 9. This plug closure 11 is preferably made of sheet metal which is deformed to present a bottom portion 12 and side walls 13 rising from the bottom at one end and on two adjacent sides, said side walls being adapted to frictionally fit the walls 14 of the recess 9.

The recess 9 is shown as being countersunk near its open end as indicated at 15 and the closure plug 11 is formed at its periphery with a bead 16 adapted to fit within this recess. The countersink 15 is shown in Figs. 4 and 7. As stated above the bottom 12 of this closure plug is permanently secured to the tear strip 6, preferably adjacent the end thereof.

55 In manufacturing the can, the can end 3 will be made with the countersunk recess 9 as shown and the bottom of the recess will be provided with the score line 5. The closure plug 11 may then be placed in the recess and spot welded or otherwise permanently secured to the tear strip 6. The countersunk portion 15 of the recess 16 will preferably be of a depth to accommodate the bead so that when the plug is in place it comes substantially flush with the top face of the can end.

65 The closure plug 11 also constitutes the means by which the tear strip 6 may be torn loose from the end of the can in order to open the pouring opening 7 and in order to facilitate this tearing operation I propose to deform a portion 18 of the bead 16 so as to raise it slightly from the top surface of the can. This will furnish a space into which an implement, such as a screw driver 19 or the like, may be inserted for lifting the closure plug from the can.

75 If the recess 9 and the line of weakness 5 are

formed in the can end I will preferably place the recess and line of weakness adjacent the side wall of the can as shown in the drawing and in this case the deformed or raised portion 18 of the bead 16 can conveniently be at the end of the closure 5 plug adjacent the side wall of the can. With this construction the implement 19 may be inserted beneath the raised portion 18 of the bead 16 and by using the edge of the can as a fulcrum and pressing downwardly on the implement 19 the tearing of the tear strip along the line of weakness can be easily started from the curved end of the tear strip. After the tearing has been initiated then the further pulling strain to complete the tearing operation may be applied by pulling 15 upwardly on one end of the closure plug.

I have herein shown the portion of the bottom of the closure plug opposite the raised portion 18 of the bead as being inclined upwardly. This is indicated at 20 and the purpose of this is to prevent 20 the closure plug from binding in the recess 9 when it is being pried upwardly at its outer edge when the tear strip is being torn loose.

After the tear strip 6 has been torn loose from the can end as shown in Fig. 5 the contents of the 25 can may be discharged through said pouring opening.

After the can has been partially or completely emptied the pouring opening 7 may be again closed by returning the tear strip 6 and the closure plug 11 to their initial positions or to the positions they occupy before the tear strip was torn loose from the can end. When the tear strip and closure plug 11 are thus returned to their initial positions the tear strip closes the opening 7 and 35 the frictional engagement of the plug 11 within the recess 9 produces a tight seal for the opening and also serves to hold the tear strip in its closed position. Furthermore, if the can is to be opened again for discharging more of its contents this 40 can be easily accomplished by prying the closure plug 11 free from the recess 9 again.

The tongue or tear strip 6 forms a sort of hinge connection for the closure plug in its movement from open to closed position and vice versa and 45 when the plug is in its closed position its tight fit in the recess 9 and countersink 15 produces a tight joint at the opening. The closure plug 11 has the further advantage that it functions as a protection for the line of weakness before 50 the can has been opened the first time. Since the bottom of the plug 11 is larger than the tear strip said plug will overlie the line of weakness and thus protect it during shipment or handling of the can. This avoids the possibility that the 55 can will become accidentally punctured at any point along the line of weakness between the time that it has been sealed and the time when it is to be opened.

It will be observed that with this invention 60 I have provided a hermetically sealed can which is opened by tearing a tear strip loose from the can, and which is provided with a plug closure hinged to the can and operating to close the pouring opening with a friction fit.

65 When the can is opened the tear strip will be given a gradual rather than a sharp bend at the point where it is integrally connected with the can wall and as a result there is no danger that the opening and closing repeatedly of the 70 pouring opening will cause the tear strip to break off.

I claim:

1. A container having a recess formed in one wall thereof and having a line of weakness formed

in the bottom of the recess which line of weakness defines a tear strip, and a closure plug secured to said tear strip and having a shape to fit the recess.

5. 2. A container having a recess formed in an end wall thereof, the bottom of the recess being scored to form a line of weakness which partially encloses a portion of the wall of the container constituting a tear strip, a closure plug fitting said recess and permanently secured to said tear strip, said closure plug being provided with a lip raised slightly from the end of the container under which an implement may be inserted to apply force to the plug for tearing the tear strip from the container end along said line of weakness.

20. 3. A sheet metal can having a line of weakness in one wall thereof defining a tear strip, which, when separated from the wall along said line of weakness, forms a pouring opening in said wall, and a closure member for the pouring opening permanently secured to the tear strip, said tear strip forming a hinge connection for said closure after the can has been opened.

25. 4. A hermetically sealed sheet metal can having in one wall thereof a tear strip, the edges of which are united to said wall by a hermetically-sealed but readily disruptable connection, whereby when pulling strain is applied to the tear strip it will be torn loose from the wall thereby forming a pouring opening in said wall, and a closure member for said pouring opening permanently secured to said tear strip, said can having a closure-receiving portion in which the closure frictionally fits when it is closing the pouring opening.

30. 5. A hermetically sealed sheet metal can having a tear strip in one wall thereof, the edge portions of which are connected to said wall with an easily tearable but hermetically sealed connection, whereby when pulling strain is applied to the tear strip it will be torn partially loose from said wall, thereby forming a pouring opening, and a closure member for said pouring opening permanently secured to said tear strip.

35. 6. A hermetically sealed sheet metal can having a tear strip in one wall thereof, the edge portions of which are connected to said wall with an easily tearable but hermetically sealed connection, whereby when pulling strain is applied

to the tear strip it will be torn partially loose from said wall, thereby forming a pouring opening, and a closure member for said pouring opening permanently secured to said tear strip, the latter serving as a hinge connection between 5 the closure member and the can.

7. A can having a recess formed in an end wall thereof, the top of the recess being countersunk and a portion of the bottom of the recess constituting a tear strip which is connected to 10 the circumjacent part of the recess bottom by a readily tearable connection, a closure plug permanently secured to the end of the tear strip portion and frictionally fitting said recess and having at its periphery a bead which frictionally 15 fits the countersunk portion of the recess.

8. A can having a recess formed in an end wall thereof, the top of the recess being countersunk and a portion of the bottom of the recess constituting a tear strip which is connected to the 20 circumjacent part of the recess bottom by a readily tearable connection, a closure plug frictionally fitting said recess and having at its periphery a bead fitting the countersunk portion of the recess, the bottom of said closure plug being 25 permanently secured to the end of the tear strip portion and the portion of said closure bottom opposite its point of attachment with the tear strip inclining upwardly to the bead.

9. A container having a line of weakness in one 30 wall thereof defining a tear strip, which, when separated from the wall along said line of weakness, forms a pouring opening in said wall but remains permanently connected to said wall, and a closure member for the pouring opening 35 permanently secured to the tear strip, said tear strip providing means for permanently connecting the closure to the container after the latter has been opened.

10. A hermetically sealed sheet metal contain- 40 er having a tear strip in one wall thereof, the edge portions of which are connected to said wall with an easily tearable but hermetically sealed connection, and a closure member permanently secured to said tear strip whereby when pulling 45 strain is applied to the closure the tear strip will be torn loose from said wall, thereby forming a pouring opening, said closure being usable to reclose said opening.

HARRY SEBELL. 50
